FLOWER POT HOLDER Charles G. Dallas, 108 Broadway,
Mantua Terrace, N.J. 08051

Filed June 21, 1971, Ser. No. 155,380

Term of patent 14 years

Int. Cl. D11—02

U.S. Cl. D35—3 C

FIG. 1FIG. 2

FIG. 1 is an elevation side view of the flower pot holder showing my new design; and

FIG. 2 is a perspective view thereof, with the support member broken away for convenience of illustration.

I claim:

The ornamental design for a flower pot holder, as shown, and described.
